UNITED STATES PATENT OFFICE

156,786

AMPHIBIAN AIRPLANE

Moulton B. Taylor, United States Navy

Application June 21, 1945, Serial No. 120,236

Term of patent 14 years

(Cl. D71—1)

To all whom it may concern:

Be it known that I, Moulton B. Taylor, a citizen of the United States and an officer in the United States Naval Reserve, have invented a new, original, and ornamental Design for Amphibian Airplanes, of which the following is a specification, reference being had to the accompanying drawings, forming part thereof.

Fig. 1 is a top plan view;

Fig. 2 is a front elevational view; and

Fig. 3 is a side elevational view of an amphibian airplane, showing my new design.

The invention described herein may be manufactured and used by or for the Government of the United States of America for governmental purposes without the payment of any royalties thereon or therefor.

I claim:

The ornamental design for an amphibian airplane, as shown.

MOULTON B. TAYLOR.
